United States Patent Office.

JOSEPH DAVIDSON, OF XENIA, OHIO.

Letters Patent No. 90,509, dated May 25, 1869.

IMPROVED DOUGH-MIXING MACHINE

The Schedule referred to in these Letters Patent and making part of the same.

To whom it may concern:

Be it known that I, JOSEPH DAVIDSON, of Xenia, in the county of Greene, and State of Ohio, have invented certain new and useful Improvements in Machines for Mixing Dough; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to machines for mixing dough, and consists in the novel construction and arrangement of certain mechanical devices for thoroughly mixing the materials composing the dough, and delivering the same, ready for use, as hereinafter explained.

In the drawings—

Figure 1 is a vertical cross-section on the line $x-x$ of fig. 2, and

Figure 2 is a vertical longitudinal section on the line $y-y$ of fig. 1.

In constructing my machine, I make a cylinder, A, of any size desired, and out of any suitable material, and secure it firmly between two end pieces, B, by tie-rods c, as clearly shown in fig. 2. These end pieces B thus form the heads of the cylinder A, and also are made so as to form a frame for its support, as shown in the same figure.

The upper side of the cylinder A, I provide with an opening, having a hinged door, a, for closing it, as shown in both figures, and in its centre, longitudinally, mount a shaft, C, provided with a series of radial arms, or beaters, i, which extend nearly to the inner surface of the cylinder, and have T-shaped heads, or scrapers i.

The shaft C has its bearings in the end pieces, in such a way as to turn freely, and on the front side projects far enough beyond the bearing to receive a pinion, G, and crank I. If it is desired to use other than hand-power to operate the machine, a pulley or other suitable device may be substituted for the crank.

Against the under side of the cylinder A, I place a slightly-conical, or tapering receiver, D, arranged so that its smaller end may project a little beyond the face of the end piece B, as shown in fig. 2.

In the bottom of the cylinder A, I make an opening, K, so located and arranged as to communicate directly with the receiver D, which has a corresponding opening, and provide a slide, J, as seen in the same figure, for closing it.

In the rear end of the receiver, and immediately under the opening, K, I locate a screw, E, by attaching it to a shaft, F, mounted in the rear end of the receiver, and the end piece, or frame B, so as to turn freely, and, to the outer end of this shaft F, I attach a gear-wheel, H, of any suitable size, so as to mesh into the pinion G, as clearly shown in fig. 2.

In operating my machine, I first close the opening, K, by the slide J, open the door a, and put in the flour, water, and other materials, if any. The door a is then closed and fastened, and the shaft C, with its radial arms, or stirrers, revolved rapidly by the crank I. As soon as the mixing is complete, the slide J is withdrawn, and the dough, passing down upon the screw E, is driven forward, and delivered through the small end of the receiver D.

The radial arms, or stirrers i, not only thoroughly mix the dough, but their T-headed ends keep it from sticking to the inner surface of the cylinder, by scraping it away.

The tapering form of the receiver D causes the dough to be delivered from it in a compact, instead of a spongy state, and ready for the rolls or breaks, if intended for crackers.

I have found, by actual experiment, that a machine thirty-six inches long and eighteen inches in diameter, run by a four-inch belt, will thoroughly mix one-third of a barrel of flour, without any previous preparation, and deliver it in just three and one-half minutes, ready for the breaks, and that it does not require more than two-thirds of the breaking that is required when mixed by hand.

Having thus described my invention,

What I claim, is—

1. A dough-mixing machine, consisting of the cylinder A, having a shaft, C, with radial T-headed arms attached, and provided with an opening, K, and slide J, communicating with a conical receiver, D, having a screw, E, therein, mounted on a shaft, F, the whole constructed and arranged to operate substantially as herein described.

2. The combination of the cylinder A and the conical, or tapering receiver D, with screw E mounted therein, when arranged with a communicating opening, K, provided with slide J, substantially as herein described, and for the purpose set forth.

JOSEPH DAVIDSON.
